[57] CLAIM

The ornamental design for a printer for a computer,
substantially as shown and described.

DESCRIPTION

FIG. 1 is a top, front perspective view of a printer for a computer showing my new design, the paper guide
being in the raised position;

FIG. 2 is a top plan view of the printer shown in FIG.
1 with the paper guide in the lowered position;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof.
